Archibald S. Murphy INVENTOR.

UNITED STATES PATENT OFFICE.

ARCHIBALD S. MURPHY, OF ROANOKE, VIRGINIA.

SURFACE-DRAINAGE OUTLET FOR SWIMMING POOLS AND THE LIKE.

Application filed July 3, 1922. Serial No. 572,633.

To all whom it may concern:

Be it known that I, ARCHIBALD S. MURPHY, a citizen of the United States, residing at Roanoke, in the county of Roanoke and 5 State of Virginia, have invented new and useful Improvements in Surface-Drainage Outlets for Swimming Pools and the like, of which the following is a specification.

My invention relates to improvements in 10 surface drainage outlets for swimming pools and the like wherein the outlets is preferably placed at or near the center of the pool, and consists mainly, of a pair of water-tight chambers, one within the other the outer 15 chamber having a plurality of openings whose lower edge is slightly above the top line of the inner chamber.

The advantages of such an outlet as my invention embodies are, first, the drainage of 20 the scum, and second the increased surface flow attained.

A typical drainage outlet of my invention is shown on the accompanying drawings, in which Fig. 1, is a vertical cross section 25 through such an outlet. Fig. 2, is an enlarged scale drawing of the restricted throat opening and Fig. 3, is a horizontal cross-section taken on the line A—A Fig. 1.

In Fig. 1,—1 are the exterior walls of 30 the outer watertight chamber 2, 2, being the throat discharge inlets at the bottom, 3, 3,

being the main outlets for surface drainage. 4, 4, are the walls of the inner chamber, which together with walls 1, 1 form the supplementary water space 5, 5. At 6, is shown 35 the discharge lip of the inner chamber, which is slightly lower than the openings 3, 3. At 3^a, 3^a, are shown the restricted throats of the water spaces or channels, 5, 5. At 7, is shown the inner spillway chamber, having 40 at its bottom the drain outlet 8. At 9 is shown a diving platform or any suitable or convenient top-structure. At 10, is indicated the bottom pool outlet, through the pipe 10^a, controlled by the valve 11, with an extensible 45 stem 12, terminating in the handwheel 13. Similar numerals refer to similar parts on the several views.

I claim:

In a surface drainage outlet, the combination of a pair of concentric water-tight chambers, having a waterspace between the walls of the first and second chambers, openings at the bottom of the outer chamber, 50 openings at the top of the outer chamber, 55 and the top edge of the inner chamber at a slightly lower distance below the lower edge of the upper opening in the outer chamber.

ARCHIBALD S. MURPHY.
